UNITED STATES PATENT OFFICE.

EDGAR M. BIRDSALL, OF BUFFALO, NEW YORK, ASSIGNOR TO MARY BIRDSALL, OF SAME PLACE.

VALVE-GEAR.

SPECIFICATION forming part of Letters Patent No. 403,455, dated May 14, 1889.

Application filed December 29, 1888. Serial No. 294,929. (No model.)

To all whom it may concern:

Be it known that I, EDGAR M. BIRDSALL, of the city of Buffalo, in the county of Erie and State of New York, have invented new and useful Improvements in Valve-Gears for Steam-Engines, of which the following is a specification.

This invention relates to that class of valve-gears for steam-engines in which the valve-actuating eccentric is mounted upon the driving-shaft in such manner that its position with reference to the shaft can be readily changed or shifted so as to reverse the motion of the engine, or be adjusted so as to cut off the supply of steam to the cylinder-ports at any desired point of the stroke of the piston.

The object of my invention is to provide a simple, reliable, and inexpensive mechanism, whereby the position of the eccentric upon the shaft can be readily shifted or changed, as desired; and the invention consists in the peculiar construction of the parts, as will be hereinafter more fully described, and pointed out in the claims.

In the accompanying drawings, consisting of two sheets, Figure 1 is a longitudinal sectional elevation of my improved valve-gear applied to the crank-shaft of a steam-engine. Fig. 2 is a top plan view of the same, partly in section. Fig. 3 is a cross-section in line $x-x$, Fig. 1. Figs. 4 and 5 are cross-sections in line $y-y$, Fig. 1, looking in opposite directions. Figs. 6 and 7 are cross-sections in lines $z-z$ and $w-w$, Fig. 1, respectively. Fig. 8 is a fragmentary horizontal section of the eccentric and connecting parts. Fig. 9 is a fragmentary horizontal section of the lever whereby the eccentric is shifted, showing the worm-pinion in elevation.

Like letters of reference refer to like parts in the several figures.

A represents the crank-shaft of a steam-engine supported in bearings $a-a'$, and A' represents the crank-disk secured to one end of the shaft A.

B represents the eccentric provided with a slot or elongated opening, b , through which the shaft A passes.

C represents a supporting-disk secured to

the shaft A adjacent to the eccentric B, and to which the latter is movably attached by transverse V-shaped guides c , arranged in corresponding guide-ways, $d-d$, formed on or secured to the adjacent side of the supporting-disk C. This construction permits the eccentric B to be shifted laterally on the disk C, so as to increase or diminish the degree of its eccentricity with reference to the shaft A and change its stroke accordingly.

E represents the eccentric-rod shown in dotted lines in Figs. 1 and 2, whereby motion is transmitted from the eccentric B to the engine-valve in the usual manner.

F represents a casing surrounding the shaft A on the inner side of the disk C, and secured to the latter by longitudinal screw-bolts f .

The casing F is divided longitudinally into two parts or shells, $f'-f^2$. These shells are provided at their inner ends with inclined segmental ribs or faces f^3 , which fit into a correspondingly-inclined seat or socket, f^4 , formed on the inner side of the disk C. These inclined faces serve to tightly clamp the shells $f'-f^2$ of the casing F against each other, and form a rigid connection with the disk C when the shells are forced into the socket f^4 by the screw-bolts f . The inner ends of the shells $f'-f^2$ are clamped together on one side of the casing F by a transverse screw-bolt, f^6 . The rim f^5 , forming the socket f^4 , may be used as a pulley for the governor-belt.

The disk C and casing F are caused to revolve with the shaft A by means of a radial pin, g , secured to the shaft A and entering an opening, g' , formed in the meeting faces of the shells $f'-f^2$, as clearly shown in Figs. 1 and 2. The pin g also serves to hold the parts against longitudinal movement on the shaft A.

G represents a shifting-lever arranged in a chamber, g^2 , formed in the casing F, on one side thereof, and swinging upon the pin g , as clearly shown in Figs. 1, 2, and 9. The inner arm, g^3 , of the lever G passes through an opening, h , formed in the disk C, and a recess, h' , formed in the adjacent side of the eccentric B, and engages in an opening, h^2 , formed in a cylindrical block, H, as clearly shown in Fig. 8. The block H is seated in a circular opening, i , arranged in a cross-bar, i' , formed on the

eccentric B, so as to be free to turn in its seat when the eccentric is shifted. The openings *h h'* are made sufficiently large to allow of the requisite movement of the lever G in shifting the eccentric. The arm *g³* of the lever G is free to move inwardly and outwardly in the block H when the eccentric is shifted, whereby binding of the parts is prevented.

I represents a worm-segment arranged at 10 the inner end of the shifting-lever G, and which meshes with a transverse worm-pinion, J, mounted on the screw-bolt *f⁶* within the casing F.

As clearly shown in Figs. 1, 2, 6, and 9, the 15 worm-pinion J consists of a cylindrical drum, *j*, which is provided on its circumference with several rows of projecting gear-teeth, *j'*. The teeth of the several rows are arranged in line with each other in the longitudinal direction 20 of the drum and extend spirally around the circumference of the drum, so as to form a pinion which acts as a combined gear-wheel and worm.

K represents a longitudinally-movable 25 rack-bar which engages with the teeth *j'* of the pinion J, and whereby the latter is rotated and the lever G shifted. The gear-rack K passes through an opening, *k*, in the outer end of the casing F, and is provided on its inner side with a key or feather, *k'*, which engages in a groove or way, *k²*, formed in the shaft A, whereby the rack-bar is compelled to rotate with the shaft A, while being free to move lengthwise on the shaft.

K' represents a collar formed with or secured to the outer end of the rack-bar K and encircling the shaft A, whereby the rack-bar is held against lateral displacement. The inner end of the rack-bar is bifurcated, as shown 40 in Figs. 1 and 4, so that it can pass by the pin *g*.

L represents a longitudinally-movable rack-bar arranged a short distance above the shaft A, and which is guided in its movements on 45 a lug or way, *l*, formed on the upper portion of the bearing *a'*, on one side thereof, as clearly shown in Fig. 7. The rack-bar L is attached to the collar K' by a yoke, *l'*, which fits in an annular groove, *l²*, formed in the 50 periphery of the collar K'.

m represents a stationary rack-bar secured to the upper side of the bearing *a'*, opposite the rack-bar L, and n is a gear-wheel meshing on one side with the movable rack-bar L and 55 on its opposite side with the fixed rack-bar m. The gear-wheel n is supported upon shoulders or ledges *n' n²*, formed on the rack-bars L and m, and is held in place between the rack-bars by a horizontal plate, *n³*, secured to the top of the stationary rack-bar.

p represents a short vertical shaft or stud secured to the gear-wheel n, and which passes upwardly through a longitudinal slot or elongated opening, *p'*, formed in the 60 plate *n³*,

p² represents a shifting-rod, which is connected with the axle *p* of the gear-wheel n by

an arm, *p³*. The shifting-rod *p²* is actuated in any ordinary and well-known manner.

Upon turning the wheel *n* in one or the other direction by the rod *p²* and arm *p³* it is caused to travel inwardly or outwardly on the stationary rack-bar *m*, and thereby move the rack-bar L and the rack-bar K about twice the distance that the wheel *n* travels on the 75 rack-bar *m*. This movement of the rack-bar K causes the pinion *j* to revolve and swing the shifting-lever G on its pivot, and the latter in turn shifts the eccentric B on the shaft A. It will thus be seen that but a short 80 movement of the rod *p²* is required to shift the eccentric.

The worm-pinion J is held against lateral movement between the shells *f' f²* of the casing F, and thereby serves to securely lock 85 the eccentric in position after being shifted.

I claim as my invention—

1. The combination, with the crank-shaft, of a supporting-disk secured to said shaft, an eccentric capable of movement on said support, a shifting-lever pivoted to said shaft, whereby said eccentric is shifted, and a worm whereby said shifting-lever is actuated, substantially as set forth.

2. The combination, with the shaft A, the support C, secured thereto, and an eccentric capable of movement on said support, of a shifting-lever connected with said eccentric, a worm provided with gear-teeth whereby said shifting-lever is actuated, and a gear-rack 100 whereby said worm is rotated, substantially as set forth.

3. The combination, with the shaft A, the support C, secured thereto, and the eccentric B, capable of movement on said support, of a movable block, H, seated in said eccentric, a shifting-lever movably attached to said block and provided with a gear-segment, a worm engaging with said gear-segment, and a longitudinally-movable rack-bar whereby said 110 worm is rotated, substantially as set forth.

4. The combination, with the shaft A, the support C, secured thereto, and an eccentric capable of movement on said support, of a shifting-lever connected with said eccentric 115 and provided with a gear-segment, a longitudinally-movable rack-bar, and a pinion provided with several rows of teeth arranged in line with each other lengthwise of the pinion and extending spirally around the same, 120 substantially as set forth.

5. The combination, with the shaft A, the support C, and the eccentric B, arranged movably on said support, of a casing, F, surrounding the shaft, a pin, *g*, whereby said support and casing are secured to said shaft, a shifting-lever, G, pivoted to said pin, connected at one end to said eccentric and provided at its opposite end with a gear-segment, a combined worm and gear pinion, J, arranged 125 in the casing F and engaging with said gear-segment, and a gear-rack whereby said worm-pinion is rotated, substantially as set forth.

6. The combination, with the shaft A, the

- support C, and the eccentric B, capable of movement on said support, of a tapering socket, f^4 , formed on said support, a casing, F, having beveled faces f^3 engaging in said socket, screw-bolts f , whereby said beveled faces are forced into said socket and said casing is secured to said support, a pin, g, whereby said casing is secured to said shaft, a worm-pinion, J, mounted in said casing, a shifting-lever, G, pivoted to said pin and engaging with said eccentric and with said worm-pinion, and a gear-rack, K, engaging with said worm-pinion, substantially as set forth. 5
- 15 7. The combination, with the shaft A, the disk C, and the eccentric B, supported on said disk and capable of movement thereon, of a casing, F, composed of sections f' f^2 , surrounding said shaft and provided with inclined faces, a tapering socket formed on said disk and engaging over said inclined faces, screw-bolts f , whereby the inclined ends of said sections are forced into said socket and against each other, a transverse screw, f^6 , 20 connecting the outer ends of said sections, a 25 worm - pinion, J, mounted on the screw f^6 within the casing F, a shifting-lever, G, engaging with said eccentric and provided with a gear-segment engaging with said worm, and a gear-rack K, whereby said worm is rotated, 30 substantially as set forth. 35
8. In a valve-gear, the combination, with the shaft A and the disk C, of the eccentric B, capable of movement on said disk, the eccentric-shifting mechanism mounted on said shaft and rotating therewith, a stationary rack-bar, m, a movable rack-bar, L, connected with the eccentric-shifting mechanism, a gear-wheel, n, meshing with the rack-bars m and L, and mechanism whereby said gear-wheel 40 is rotated, substantially as set forth.

Witness my hand this 13th day of November, 1888.
